UNITED STATES PATENT OFFICE.

LEOPOLD RAAB, OF VIENNA, AUSTRIA.

INTERNAL-COMBUSTION ENGINE.

Application filed March 31, 1926, Serial No. 98,799, and in Austria April 8, 1925.

This invention relates to an internal-combustion engine of the kind in which the scavenging and charging of the cylinder are effected by means of air supplied by a compressor, and the invention consists essentially in providing means whereby the scavenging and charging are effected from separate compression chambers in the same compressor, the latter being provided with two ports which are successively set into communication with the cylinders and which communicate with different compression chambers at the time of induction.

By this arrangement a very simple mechanism is obtained whereby an effective scavenging and a uniform charging of all the cylinders will be achieved.

Fig. 1 of the accompanying drawings represents an axial section of a two-stroke engine having four radially arranged cylinders which revolve about a stationary crank shaft, and

Figs. 2, 3 and 4, are sectional views of other, different types of engines to which the invention is applicable.

Fig. 5 is a section across the compressor shown in Fig. 1,

Fig. 6 is a sectional view taken through one of the cylinders, and
Fig. 7, a sectional view on an enlarged scale of that part of the compressor which contains the ports and the channel through which they communicate.

In the construction according to Figs. 1 and 5 to 7 the engine is enclosed in a casing 2 which carries a stationary crank shaft 1. Four cylinders 7 are arranged radially about a crank casing 8 which is supported on the shaft by means of ball bearings and which revolves together with the cylinders about the crank. The connecting rods 4 of the pistons 6 are associated with a ball-bearing 3 which turns about the crank pin, one of the connecting rods being rigidly secured by means of a bolt 5 to the ball-bearing so as to control the latter while the other rods are capable of angular displacement relative to the bearing. Connected to one side of the casing 8 so as to rotate with the latter, is a compressor casing 9 which encloses a compressor body mounted rigidly on the shaft 1. The compressor body is formed of two drum-shaped elements 12 and 13 which are coaxial and which are eccentric relative to the shaft and to the casing 9 so that a crescent-shaped compression space is

formed between the circumference of the drums and that of the casing. Eight vanes 17, distributed about the compressor body, rotate with the casing 9 and divide the crescent-shaped compression space into a plurality of separate compression chambers. The headed outer edges of the vanes are guided in recesses 9^a formed by U-shaped radial extensions of the wall of the casing 9. The vanes are guided by the compressor body and reciprocated by the latter in the recesses 9^a. They are also controlled by a ring 15 to which they are connected by means of bolts 16 and forked arms. The ring 15 is located between the drums 12 and 13 and supported on their adjacent bosses by means of a ball-bearing 14. Ducts 17^a carried obliquely through the heads of the vanes allow the air to pass in and out of the recesses 9^a. A flange 18 on the drum 12 forms a tight fit with the casing 9 and limits the compression space at the engine side of the compressor. The flange is uniform and concentric with the compressor casing 9. The outer end of the compressor is closed by a plate 22 which rotates with the casing 9 which supports the end of the shaft 1 by means of a ball-bearing. The plate 22 carries a shaft 23 whereby it is supported by means of a ball-bearing in the end plate 24 of the casing 2, the shaft 23 being utilized for transmitting the motion of the engine to outside elements. The opposite end of the shaft 1 is hollow and contains the stem 33 of a funnel through which air is admitted into the crank chamber 8. The air admission is regulated by means of a throttle valve 34. From the crank chamber the air passes through apertures 35 in the chamber wall 36 into the compressor drum 12 whence it goes through peripheral apertures 36 into the compression space. A channel 19 in the compressor drum 12 communicates, at one end of the compression space, with the different compression chambers in succession. It also communicates with two spaced ports 20 and 21 which open through the flange 18 and which are normally closed by the adjacent wall of the compressor casing 9. The induction and exhaust ports of the cylinders are made in the cylinder sides so as to be controlled by the pistons 6. The induction port 11 is carried through the adjacent wall of the casing 9 so that while it is normally closed by the flange 18, it passes across the ports 20 and 21 in succession so as to

admit the air from the compression chambers into the cylinder. The spacing of the ports 20 and 21 equals substantially that of the vanes so that one chamber will be emptied through the port 20 and the next chamber through the port 21. The port 21 supplies the charging air and contains an atomizing nozzle 40 for the fuel which is admitted to the nozzle through ducts 37 and 38 carried through the shaft 1 and through the compressor drum 12. The nozzle 40 is surrounded by a sleeve 44 through and outside of which the air passes. A needle valve 42 controlled by a sleeve 41 and a spring 43, maintains the atomizing nozzle 40 normally closed and opens under the air-pressure. The duct 38 opens through a nozzle 39 into a space behind the nozzle 40. This space opens through the periphery 26 of the compressor drum 12 where it is closed by a screw stopper 45. An aperture in the periphery of the casing 9, normally closed by a screw stopper 46, is arranged so as to pass across the stopper 45 and allow 25 it to be removed for cleaning and exchanging the nozzle 39 without dismounting any other parts of the engine casing.

The exhaust ports 47 of the cylinders are situated farther from the cylinder heads than the induction ports so as to be opened later and closed before the latter by the pistons. The exhaust ports open into shells 10 which are connected to the compressor casing 9. The tubular outlets of the shells 35 are directed obliquely away from the rotating direction, and the orifices are cut aslant, as shown in Fig. 6, so as to produce a suction effect in the interior of the shells. The casing 2 receives the exhaust and discharges 40 it at 25 through a funnel 26 formed in the lower part of the casing.

The sparking plugs 7^a are screwed into the heads of the cylinders, and the walls are depressed inwards so as to form, around 45 the lug and its sparking points, valleys wherein oil particles will be collected owing to the centrifugal force and burnt without contaminating the sparking points.

The casing 8 carries a pinion 29 which 50 meshes with the driving wheel 30 of the ignition apparatus 27 and also with the driving wheel 31 of the lighting dynamo 28. The wheel 31 has a cam whereby it actuates a spring-supported plunger 50 acting as a 55 lubricating pump.

The casing 2 has a detachable cover 32.

The action is as follows:—

As seen in Fig. 5, the cylinders and the compressor casing revolve in anti-clockwise 60 direction. Air is admitted to the widest portion of the compression space and is compressed between the vanes as it is conveyed by the latter to the narrow portion of the space. In each cylinder the cycle of operations is completed while the cylinder moves

once around the crank shaft. Considering the piston movement in terms of angular cylinder displacement, the induction port is uncovered by the piston 70° before and closed 70° after the outer dead centre position of the piston, while the exhaust port remains open 50° at each side of the same dead centre position. The induction port is also controlled by the compressor drum 12 and remains closed until the piston has 75 moved through 30° with open exhaust port. In Fig. 5, the port 11 of the cylinder *a* is just about to pass the port 20 of the air compressor, and the chamber *b* of the compressor is about to enter into communication 80 with the channel 19 for supplying scavenging air to the cylinder. The ports remain in communication during 45° of the cylinder displacement, i. e., 20° before and 25° after the dead centre position, so that a 85 thorough scavenging of the cylinder will take place. 15° later, i. e., 40° after the dead centre position of the piston, the cylinder port enters into communication with the port 21, and the next compression chamber 90 *c* enters into communication with the channel 19. The compressed air in the latter chamber then enters the cylinder and it also opens the needle valve 42 so that the air will be mixed with the atomized fuel. After 95 10° admission the exhaust port is closed and after another 20° the admission of fuel mixture ends by the closing of the induction port by the compressor as well as by the piston. During the next 110° of the cylinder displacement the admitted fuel mixture is compressed in the cylinder, and the next following power stroke extends over a cylinder displacement of 130°, i. e., until the exhaust 105 port is reopened.

Since all the cylinders pass the compressor ports 20 and 21 in succession, and since for each cylinder two compression chambers will discharge their air, as described in connection with the chambers *a* and *b*, into the channel 19, it is evident that the same process will be repeated for each cylinder in succession. It is by allowing 90° cylinder displacement for the scavenging and charging of each cylinder, that the four cylinders are 110 thus enabled to cooperate with the same compressor ports. By keeping the scavenging air separate from the charging air, the compressor can be throttled down to a very small supply of fuel mixture for slow engine speed. 115 If different volumes of air should be required for scavenging and charging, the respective vanes 17 may be arranged at different distances apart.

The invention is also applicable to engines with stationary cylinder and rotating crank shaft, as shown in Figs. 2 to 4. In the arrangement according to Fig. 2, the compressor is arranged beside the cylinder or cylinders and admits the air in the first 120

place into the crank chamber 51 where it is compressed by the piston 6 and returned to the compressor. As the latter thus receives pre-compressed air it can be of very small dimensions. The compressor 13 is driven by the crank shaft.

Fig. 3 shows an arrangement which operates in the same manner, the compressor being here situated between cylinders arranged at an angle relative to one another.

In connection with twin cylinders, such as shown in Fig. 4, the compressor arrangement is particularly advantageous as regards economic working. The operation is here the same as that described in connection with Fig. 2. Twin cylinders of this type may also be used in the case of engines with revolving cylinders.

The compressor arrangement is also suitable for use in connection with four-stroke engines, it being driven from the crank shaft at a transmission ratio of 1:2 or 1 to 4.

In the two-stroke engine, a reversal of movement may be brought about by an adjustment of the compressor body containing the channels.

Engines constructed according to the invention will work satisfactorily with very heavy fuel.

I claim:

1. In an internal-combustion engine, a rotary air compressor having a crescent-shaped compression space, means for maintaining in said space a plurality of independent compression chambers, and means for scavenging and charging the engine with air from different alternate compression chambers.
2. In an internal-combustion engine having the features claimed in claim 1, a rotary air compressor having two outlet ports, means for setting said ports successively into communication with the engine cylinders, and means for supplying air to said ports from different compression chambers.
3. An internal-combustion engine having

the features claimed in claim 1 and wherein the compression chambers for scavenging and charging are of different dimensions.

4. In an internal-combustion engine having the features claimed in claim 1, a rotary air compressor having two outlet ports and a channel through which said ports communicate, means for setting said ports successively in communication with the engine cylinders, and means for setting the channel in communication with different compression chambers while different ports communicate with the same cylinder.

5. In an internal-combustion engine, the combination with cylinders whose ports are controlled by the pistons and wherein the induction port is opened before the exhaust port, of a rotary air compressor which also controls the induction port, vanes in said compressor forming a plurality of independent compression chambers, means for setting one of said chambers in communication with the induction port so as to supply scavenging air to the cylinder during the latter part of the outward stroke of the piston and during the commencement of the return stroke, and means for setting the next following compression chamber in communication with the induction port before the exhaust port is closed so as to supply charging air to the cylinder.

6. The structure claimed in claim 5 and a crank casing communicating with the cylinders so as to form a pump space, said crank casing being in communication with the air compressor so that air is first sucked into the casing and then passed to the compressor.

7. An internal-combustion engine according to claim 5 having a stationary crank shaft and a revolving set of radially arranged cylinders, the movable compressor elements being associated with said cylinders and the stationary elements with the shaft.
